UNITED STATES PATENT OFFICE

FRED C. TRUESBURY, OF ROCKFORD, ILLINOIS, ASSIGNOR TO J. L. CLARK MANUFACTURING CO., OF ROCKFORD, ILLINOIS, A CORPORATION OF ILLINOIS

CONTAINER

Application filed July 23, 1933. Serial No. 294,729.

This invention relates to improvements in containers for powdered and granular materials such as condiments, and more particularly to a means for regulating the quantity of material which may be withdrawn from such a container.

One object of the invention is to provide a new and improved outlet valve structure for condiment cans and the like by which 10 different and accurately measured quantities of the powdered contents may be withdrawn from the can by the use of a spoon pressed against edges of different curvatures at the mouth of the container.

15 More specifically stated the invention resides in the novel shape and arrangement of cooperating openings in the end wall and cover movably mounted thereon, which arrangement enables level and heaping spoon- 20 fuls of the container contents to be withdrawn and the container to be effectually and conveniently closed by turning said cover through a partial revolution.

Another object relates to the location of 25 the defining edges of the container mouth so that a mouth of the proper size and shape results for enabling measured spoonfuls of the material to be withdrawn as above set forth from small round containers having rotatable closure members in direct sliding contact 30 with their end walls.

Other objects and advantages of the invention will become apparent from the following detailed description taken in connection with the accompanying drawings in 35 which,

Figure 1 is an elevational view of a container embodying the features of the present invention.

40 Fig. 2 is a plan view showing the end closure wall of the container.

Fig. 3 is a sectional view taken along the line 3—3 of Fig. 2.

45 Fig. 4 is an end view of the container showing a spoon in section to illustrate the manner in which a level spoonful of material may be withdrawn from the container.

50 Fig. 5 is a similar view illustrating how a heaping spoonful of the material may be withdrawn.

While the container illustrated in the drawings embodies the preferred form of the invention, it is to be understood that I do not intend to be limited by the particular form disclosed, but aim to cover all modifications and alternative constructions falling within the spirit and scope of the invention as expressed in the appended claims.

In the drawings, the invention is embodied in a container construction having a tubular body 6 of cylindrical form closed at one end by a flat wall 7 and at the other end by the curved top wall 8. In the present instance the wall 8 is formed with a peripheral flange 9, which is snugly received upon and permanently secured to the end of the body 6 above an annular bead.

Punched or otherwise suitably formed in the end wall 8, is an elongated crescent-shaped orifice 10 extending circumferentially 70 around the wall 8 and being of sufficient size as to allow for the convenient entry and withdrawal of a spoon of predetermined size, such as the average teaspoon. The orifice 10 is disposed eccentrically of the container axis 75 and is defined by two intersecting edges 11 and 12 of predetermined contour spaced from the side walls of the body 6 and both disposed to one side of the longitudinal axis of the container. The inner edge 11, which is disposed nearer the axis of the body 6, is made substantially straight in the present instance for the purpose of forming a level spoonful of the material when the spoon is withdrawn from the container. While the other edge 12 follows generally the peripheral contour of the body 6 and is disposed adjacent such periphery, its exact curvature is preferably such that a so-called heaping spoonful of the contents may be withdrawn from the container by a spoon of predetermined size.

The container is closed by a cover 13 of the same contour as the end wall 8 is fitted onto said wall in telescoping relation, being held in place by a flange 14 engaging a peripheral shoulder 15 of the flange 9. Thus, the cover is permitted to turn freely about the container axis. The curved end portion of the cover is closed except for an orifice 16 which conforms both in shape and radial position 100

to the orifice 10, so that the orifice 10 can be completely exposed by rotating the cover 13 until the two orifices are in register. An opening of any smaller size may be formed 5 by varying the angular relation of the cover 13 on the body of the container. To completely close the container the cover 13 is turned until its orifice 16 is positioned diametrically opposite the orifice 10 as shown 10 in Fig. 2.

It will be apparent that the container mouth, which is defined by the openings in the wall 8 and cover 13 when the openings are in register, must be relatively large in 15 order to admit a spoon, and the width should be somewhat greater than thickness of the bowl of the spoon. The present arrangement of the openings in the cover and wall 8 permits the use of a cover rotatable about the container axis in contact with the end wall 8. This is because the mouth of container formed by bringing the two openings into register is disposed wholly to one side of the center of 25 the end wall. Thus, by turning the cover through a partial revolution, the opening in the wall 8 may be completely closed.

The arrangement disclosed is further advantageous in that it permits the invention to be applied to containers of small diameter. 30 This is because the concave edge of the container mouth extends along the periphery of the end wall which is of similar curvature. The available space between the center of the wall 8 and the edge thereof is thereby 35 conserved enabling the invention to be applied in smaller containers than would otherwise be possible.

To measure out a level spoonful of the 40 contents of the container, the cover 13 is turned until the two orifices are brought into register as shown in Fig. 4 to enable a spoon 17 to be inserted into the body and filled with the contents of the container. Then with the 45 container tilted to position the straight edge 11 uppermost, as shown in Fig. 4, the spoon laden with the powdered contents is withdrawn, during which its edges 18 are pressed upwardly against the edge 11 which serves to 50 level off the contents of the spoon throughout its entire length, thereby accurately measuring out a level spoonful. The portions of the powder thus wiped off the spoon remain within the container.

To measure out a so-called heaping spoonful, the same procedure is repeated with the 55 container in inverted position from that shown in Fig. 4, that is with the curved edge 12 of the orifice 10 positioned above the edge 60 11 as shown in Fig. 5. Upon withdrawal of the spoon, the contents are leveled off to conform to the curvature of the edge 12 which, when intersecting with the edges 18 of the 65 spoon, leaves the proper quantity of material on the spoon.

I claim as my invention:

1. A container for permitting different measured quantities of its contents to be withdrawn by a spoon, said container having a side wall, an end wall having an opening 70 therein large enough to enable a spoon to be inserted therethrough, and a closure plate mounted on said end wall to turn about the center thereof in sliding contact with the wall and also having an opening therein 75 large enough to receive a spoon, said opening being shaped to form an elongated mouth corresponding in shape to the cross-section of the bowl of the spoon when the openings are in register whereby either a level or heaping 80 spoonful of the contents may be withdrawn by the spoon, said mouth being disposed wholly to one side of the axis of said cover whereby the mouth can be completely closed by turning the cover through a partial revolution. 85

2. A container for permitting different measured quantities of its contents to be withdrawn by a spoon having a circular end wall and a circular cover mounted on the end wall 90 for rotation about the center thereof and in sliding contact therewith, said wall and cover having openings therein movable in the operation of the cover into and out of registry, 95 said openings being shaped to provide in their registering relation a mouth having an inner thin straight edge offset slightly from the axis of the cover and an outer thin edge of concave curvature extending along the peripheral edge of the cover adjacent thereto, and said mouth being of a size adapted to 100 permit the bowl of a spoon to be withdrawn from the container with its side edges bearing either against said inner straight edge or said outer curved edge according to whether a 105 level or a heaping measure of material is to be removed.

In testimony whereof, I have hereunto affixed my signature.
